UNITED STATES PATENT OFFICE.

RICHARD GREGG, OF OSWEGO, NEW YORK.

STEAM-BOILER.

SPECIFICATION forming part of Letters Patent No. 624,791, dated May 9, 1899.

Application filed December 23, 1898. Serial No. 700,092. (No model.)

To all whom it may concern:

Be it known that I, RICHARD GREGG, of Oswego, in the county of Oswego, in the State of New York, have invented new and useful 5 Improvements in Steam-Boilers, of which the following, taken in connection with the accompanying drawings, is a full, clear, and exact description.

My invention relates to boilers, and more particularly to those of the locomotive type.

My object is to produce a locomotive-boiler (or other type, if desired) which is provided with water-flues, a fire-wall carried by them, a shell inclosing the water-flues and part of 15 said fire-wall and creating a passage for the smoke or products of combustion from the fire-pot through, between, and around said flues and between them and said casing forward into a smoke-chamber in the front of 20 the boiler, and thence to the rear end and to the stack opening or pipe through smoke-flues immersed in water, suitable water-legs being also provided to aid in creating and maintaining free circulation of the water both 25 through the water-flues and around the smoke-flues.

It is constructed as follows, reference being had to the accompanying drawings, in which—

30 Figure 1 is a longitudinal vertical section, partly in elevation, of my boiler. Fig. 2 is a vertical cross-section on line *x* *x* in Fig. 1. Fig. 3 is a like view on line *y* *y* in Fig. 1.

The boiler comprises a suitable outer shell, 35 a parallel inner wall 2, creating a water-leg 3 and having a fire-box 4, grate 5, ash-pit 6, with suitable openings 7 and 8 for the fuel and ash-pit doors. Between the fire-box and a point near the front end the water-leg wall 40 is carried over in the form of a cylinder *a*, the end 9 of which constitutes a flue-sheet 9, in which the front ends of the water-flues 10 are set, their rear ends being set in the water-leg wall 2, thus connecting the water-leg to the 45 water-chamber 11 in the front end of the boiler and between it and the flue-sheet 9. The upper row of said water-flues is shown as set upon an arc and as furnishing a support for the fire wall or partition 12, which 50 extends forward from the rear end to a point more or less closely adjacent to the flue-sheet 9 and in such manner as to create a channel,

conduit, or reverse passage 13 for the smoke, which passes from the fire-box forward and upward between the water-flues, to be conducted back into the smoke-chamber 14 and thence forward through the smoke-flues 15 to the stack, which is not shown. These smoke-flues are set in the sheet 16 at the front end of this smoke-chamber and in the flue-sheet 17 at the front end of the boiler. A suitable manhole, cover, and fastening 18 is also provided. The smoke-flues are all below the water-level.

It will be seen that the water will circulate 65 freely through the water-legs, the water-flues, and the water-chamber and around the smoke-flues; that the smoke passes from the fire-box up around the flues until stopped by the fire-wall, thence forward to the front end of said 70 wall and to the flue-sheet 9, thence rearward through a more or less constricted passage into the smoke-chamber, and thence forward again to the stack, in this manner the water-flues being exposed to the direct action of the 75 heat and the smoke-flues being heated to exert more or less effect upon the water around them; that the flues are in two independent sets, the one set—the water-flues—receiving the direct impact of the heat exteriorly and 80 the others the direct impact interiorly, the water-flues being for part of their length inclosed in a tubular smoke-conduit and part of their length partially inclosed in a fire-wall, which also deflects the smoke and causes it to 85 take a circuitous course.

Having described my invention, what I claim, and desire to secure by Letters Patent, is—

1. In a steam-boiler an outer shell, a fire-box, a water-leg around it, an inner smoke-shell forward of the fire-box, water-tubes set in the closed front end of said smoke-shell, extending through the fire-box and connected to the water-leg, the top row of said tubes 90 being set upon an arc, a fire-wall across said shell and supported by said row of flues and extending forward part way through said inner shell creating a fire-flue between said partition and said inner shell conducting the 95 products of combustion to a smoke-chamber above the fire-box, and a set of fire-tubes extending thence forward to the front end of the boiler to carry off the smoke.

2. In a boiler, an outer shell, a fire-box, an inner smoke-shell extending forward from the fire-box, a row of water-tubes set upon an arc and extending through the fire-box and said shell, a fire-wall partition extending through the fire-box above said water-tubes and into said shell, a reverse-flue between said shell and said fire-wall opening into a smoke-chamber above said wall, and a set of

water-surrounded smoke-tubes leading from ^{to} the smoke-chamber to the front end of said boiler.

In witness whereof I have hereunto set my hand this 12th day of December, 1898.

RICHARD GREGG.
